United States Patent Office

Des. 229,157
Patented Nov. 13, 1973

229,157

NAPKIN DISPENSER

Johnson H. Smith, Fort Worth, Tex., assignor to
Loma Corp., Fort Worth, Tex.

Filed Dec. 27, 1971, Ser. No. 212,892

Term of patent 14 years

Int. Cl. D7—07

U.S. Cl. D7—72

Fig. 2

Fig. 1

Fig. 3

FIG. 4

FIG. 5

FIG. 6

FIG. 1 is a front elevational view of a napkin dispenser showing by new design.

FIG. 2 is a top plan view thereof.

FIG. 3 is a bottom plan view thereof.

FIG. 4 is a rear elevational view thereof.

FIG. 5 is a right side elevational view thereof as seen in FIG. 1.

FIG. 6 is a vertical sectional view taken along line 6-6 of FIG. 1.

I claim:

The ornamental design for a napkin dispenser, substantially as shown.
